UNITED STATES PATENT OFFICE.

ROBERT H. LEVIS, OF ALTON, ILLINOIS, ASSIGNOR TO THE ILLINOIS GLASS COMPANY, OF ILLINOIS.

DESIGN FOR A BOTTLE.

SPECIFICATION forming part of Design No. 29,170, dated August 9, 1898.

Application filed July 18, 1898. Serial No. 686,294. Term of patent 14 years.

To all whom it may concern:

Be it known that I, ROBERT H. LEVIS, a citizen of the United States, residing at Alton, in the county of Madison and State of Illinois, 5 have invented and produced a new and original Design for a Bottle, of which the following is a specification, reference being had to the accompanying drawings, forming part thereof.

Figure I shows a side elevation made after 10 my new design. Fig. II shows a perspective view thereof.

As shown in the drawings, the leading or 15 material features of my design consist of a bottle or flask made with two flat parallel sides 1, connected by two curving narrower

sides 2, said narrower sides slightly diverging from the bottom. This body is surmounted by a sloping neck 3, which meets the parallel sides on a curve 4. The neck 3 is surmounted by a flat ring 5 near its top. 20

The design presents a neat appearance and is of striking simplicity.

What I claim as new, and desire to secure by Letters Patent, is—

The design for a bottle, as herein shown 25 and described.

ROBERT H. LEVIS.

In presence of—

E. E. BISHOP,
G. J. KENDALL.
